HIGHWAY CROSSING SIGNALING SYSTEM

Joseph E. Willing, Rochester, N. Y., assignor to
General Railway Signal Company, Rochester,
N. Y.

Application February 28, 1936, Serial No. 66,233

6 Claims. (Cl. 246—130)

This invention relates in general to signaling systems, and more particularly to a signaling system for highway crossings on railroads, which invention is of later origin than the invention disclosed in the application of Mackey Ser. No. 66,232 filed February 28, 1936 and the later filed applications of Reichard Ser. No. 74,924 filed April 17, 1936, and Field and Willing Ser. No. 66,422 filed February 29, 1936, and no claim is made herein to anything disclosed in said Mackey, Reichard or Field and Willing applications.

It is proposed in accordance with the present invention to provide a signaling system for protecting highway traffic crossing railroads, where-
in the speed of a train approaching the highway determines the point at which the highway warning is started to thereby provide a warning for a substantially uniform time prior to the actual arrival of the train at the highway. More specifically, it is proposed to provide a plurality of track sections in the railroad approaching the highway crossing, a first section being employed to detect train speeds whereby a condition of certain controlling apparatus is established in accordance with train speeds within different predetermined limits, thus dividing all train movements into a plurality of different classes according to their speed. It is then proposed to control the highway warning signal in accordance with the condition of the controlling apparatus thus established in such a manner that trains in different speed classes start the highway warning upon entering different sections whereby trains in all speed classes may arrive at the highway a substantially uniform time after the warning has been started.

Other objects of the present invention include the provision of such a highway signaling system wherein a failure of the control apparatus to properly return to a normal condition upon the completion of a train movement results in the display of a restrictive railway signal indication, whereby to indicate to a train subsequently approaching the highway that the apparatus is not functioning properly and allowing such precaution to be taken as will prevent an accident until the system can be restored to its normal operating condition.

Still other objects, purposes and characteristic features of the present invention will be obvious as the description thereof progresses, during which references will be made to the accompanying drawing which illustrates in a diagrammatic and conventional manner one specific embodiment of the present invention.

A portion of a railway track having an indicated direction of traffic from left to right is illustrated as crossing a highway represented by HW in the drawing. The portion of the railway to the left of highway HW, or the approach portion is divided into track sections 1 through 4 by insulating joints J, each section having the usual track circuit comprising a battery B (with corresponding exponent) and a track relay T (also with corresponding exponent).

A normally energized highway signal controlling relay CG is provided which may govern the operation of any desired type of warning device at highway HW such as flashing light signals, bells, crossing gates or the like, but for simplicity the relay CG has herein been shown as controlling the energization of a signal lamp HG. The signal HG is shown as deenergized in accordance with the energization of relay CG over an obvious circuit including front contacts 8, 9 and 10 of track relays T², T³ and T⁴ respectively, and relay CG may also be energized by auxiliary circuits controlled in accordance with train speeds detected in track section 1.

The different train speeds are detected in section 1 in the present embodiment by two timing devices 1TD and 2TD with respective stick repeating relays 1S and 2S. The timing devices 1TD and 2TD may be of various types, but have herein been shown diagrammatically as thermal relays which may, for example, be constructed as shown in Patent No. 1,902,793 granted to J. E. Willing, March 21, 1933.

The first section is employed as a timing section or that is, the timing devices 1TD and 2TD are conditioned during the length of time required by various trains to traverse section 1, which time is a measure of the train speed. In other words, when a train enters section 1 a circuit is completed from the (+) terminal of a suitable source of energy, through back contact 12 of relay T¹, front contact 13 of relay T², back contact 14 of relay 1S, through heating element 15 of thermal relay 1TD and through a variable resistor 16, to (—). It will be clear that the above circuit is completed only during the time in which a train is traversing section 1 as the entrance of the train into section 2 drops relay T² to open the circuit at front contact 13, and consequently the length of time in which a circuit is completed through back contact 12 and front contact 13 of track relays T¹ and T² respectively is inversely proportional to the speed of a train traversing section 1.

The variable resistor 16 of thermal relay 1TD

may now be adjusted so that the time required by a train to traverse section 1 at a certain intermediate rate of speed is just sufficient for actuating member 18 of thermal relay 1TD to engage 5 a movable contact 19 with a fixed contact 20 thereby picking up relay 1S over an obvious circuit. In this manner a high speed train can traverse section 1 without picking up relay 1S while all slower speed trains will cause relay 1S 10 to pick up, and the picking up of relay 1S deenergizes the heating element 15 of relay 1TD at back contact 14 and completes an energizing circuit for relay 2TD from (+), back contact 12 of relay T¹, front contact 13 of relay T², front 15 contact 14 of relay 1S, back contact 22 of relay 2S, through heating element 23 and through a variable resistor 24, to (-).

In this manner the slower speed trains consume a time in traversing section 1 which is 20 longer than that required to operate thermal relay 1TD, and the variable resistor 24 of relay 2TD may now be adjusted so that this additional time required by trains below a certain slow rate of speed is just sufficient for actuating element 26 to engage movable contact 27 with a 25 fixed contact 28 thereby energizing relay 2S over an obvious circuit. Intermediate speed trains then traverse section 1 in a time sufficient to pick up relay 18 but insufficient to pick up relay 2S while slow speed trains consume a longer 30 time in traversing section 1 which is sufficient to pick up both relays 1S and 2S.

Relays 1TD and 2TD with their repeating relays 1S and 2S then comprise a speed responsive 35 organization when controlled in this manner by the occupancy of section 1, whereby all train movements are divided into three classes by the condition of these relays established according to the time required by a train to traverse section 40 1. In other words, high speed trains do not pick up either relay 1S or 2S, intermediate speed trains pick up relay 1S only, while slow speed trains pick up both relays 1S and 2S. This speed responsive means is now employed to select which 45 one of sections 2, 3 or 4 is to start the warning at highway HW, or that is, high speed trains are to start the warning upon entering section 2, intermediate speed trains upon entering section 3 and slow speed trains upon entering section 4.

A high speed train as previously described 50 traverses section 1 in a time insufficient to pick up either relay 1S or 2S and consequently upon entering section 2, this high speed train deenergizes the control relay CG at front contact 8 of relay T² and the warning signal HG is energized through back contact 30 of relay CG. This 55 energizing circuit for relay CG is maintained open until the train has passed the highway HW by open front contacts 9 and 10 of relay T³ and T⁴ respectively.

An intermediate speed train, however, in 60 traversing section 1 picks up relay 1S which is held up as long as section 1 or section 2 is occupied over a stick circuit including its front contact 32 and multiple back contacts 33 and 34 of relays T¹ and T² respectively. This intermediate speed train does not deenergize relay CG upon entering section 2 as it may be seen on the accompanying drawing that a front contact 35 of 65 relay 1S shunts around front contact 8 of relay T² in a manner to maintain relay CG energized after relay T² drops, or that is, relay CG is then energized over a circuit including front contact 35 of relay 1S, front contact 9 of relay T³ and front contact 10 of relay T⁴. This intermediate speed train 70

then starts the warning upon entering section 3 by deenergizing relay CG at front contact 9 of relay T³ and thereafter maintains the warning upon entering section 4 by holding relay CG deenergized at front contact 10 of relay T⁴. 5

A slow speed train as previously described picks up both relays 1S and 2S while traversing section 1, relay 2S being held up while sections 1, 2 and 3 are occupied by a stick circuit including its front contact 31 and a front contact 38 of relay 1S in multiple with a back contact 39 of relay T³. Consequently relay CG is maintained energized while this slow speed train traverses section 2 and section 3 over a circuit including front contact 40 of relay 2S and front contact 10 of relay T⁴, 15 which circuit obviously is opened when this slow speed train enters section 4 at front contact 10 of relay T⁴, thereby starting the warning at this point.

In this manner the system can be so organized 20 that the maximum speed train which starts the warning upon entering each of the sections 2, 3 and 4 will reach the highway HW only after a period of time which is considered to be the time necessary to warn highway traffic prior to the 25 actual arrival of the train. In other words, the distance traveled by the maximum speed train in the required warning time should be the distance from the entrance end of section 2 to the highway, the distance traveled by an intermediate 30 speed train in the same time should be the distance from the entrance end of section 3 to the highway, and likewise the distance traveled by a slow speed train in this same time should be the 35 distance from the entrance end of section 4 to the highway.

During the time in which a slower speed train occupied section 1, the thermal relays 1TD and 2TD are operated as previously described to pick 40 up the respective stick relays 1S and 2S, whereupon the heating elements of the thermal relays are deenergized by contacts of the stick relays, the stick relays being held up by their stick circuits until the train has started the highway warning signal as previously described. However, 45 in the event the actuating element of either of the thermal relays fails to properly return to its normal position after the completion of a train movement, it will be clear that the operating time of the thermal relay would be considerably reduced which might permit a high speed train to establish a condition of the relays 1S and 2S ordinarily corresponding to a slow speed movement. Such a condition would of course withhold 50 the warning at the highway until the high speed train had reached section 3 or 4 so that a warning time for a dangerously short period would result.

In order to prevent such a dangerous condition from arising due to the failure of the thermal 60 relays 1TD and 2TD to be in their normal positions when a train enters section 1, it is contemplated to indicate such an abnormal condition to an approaching train whereby the train speed may be reduced or extra precautions may be 65 taken which are unnecessary during normal operation of the highway signaling system.

The illustrated means for providing such a check on the normal position of the thermal relays comprises contacts 44-45 on the thermal 70 relay 1TD and similar contacts 48-49 on relay 2TD, which contacts are only closed when the respective actuating elements 18 and 26 are in their normal positions. These contacts 44-45 and 48-49 are indicated as included in series 75

with the energizing circuit 50 of the usual home control relay H which is indicated diagrammatically as controlling a wayside railway signal RG by contact 52 in the usual manner. The home relay H is normally energized as shown to provide a clear or proceed signal indication in accordance with forward traffic conditions, and it will then be clear that this relay H will be deenergized by contacts 44-45 or contacts 48-49 to provide a restrictive signal indication unless the actuating elements or relays 1TD and 2TD are both in their normal deenergized positions.

A highway signaling system is thus provided wherein a plurality of time responsive means are distinctively conditioned in accordance with the time required for trains to traverse a first track section, whereby the condition of these timing means selects which one of several other track sections will be effective to control the starting 20 of the highway warning. The control track sections are located at different distances from the highway, and a section is then selected by the condition of the time responsive means which is located a distance from the highway proportional 25 to the train speed, thus permitting all trains regardless of size variations in speed to arrive at the highway a substantially uniform time after the warning has been started. The present system also checks the proper return of 30 the time responsive means to a normal condition at the completion of a train movement whereby to restrict railway traffic until a normal condition is restored, thereby permitting the engineer of an approaching train to proceed with such 35 precaution as will supplement any insufficient automatic warning which may result from this improper condition of the time responsive means.

In describing the present invention, attention has been directed to one specific embodiment 40 thereof without attempting to point out the various alternate or optional features of construction or the various organizations or combinations that may be employed. For example, the present system is not limited to the use of two timing devices as shown but could be organized in a very similar manner with a different number 45 of timing devices whereby to divide train movements into a larger or a smaller number of speed classes with the number of controlling track sections provided to correspond therewith. It is also to be understood that various timing devices other than thermal relays could also be employed.

In other words, the particular embodiment of 50 the present invention has been selected to facilitate in the disclosure thereof rather than to limit the number of forms which it may assume.

What I claim is:—

1. In a signaling system for highway crossings 55 on railroads, a plurality of track sections occupied successively by a train approaching the highway, a track circuit including a track relay for each section, a first slow acting device controlled by a back contact of a first track relay and a front contact of a second track relay in series, a first repeating relay controlled by the first slow 60 acting device, a stick circuit for the first repeating relay controlled by multiple back contacts of the first and second track relays, a second slow acting device controlled by a back contact of the first track relay, a front contact of the second track relay and a front contact of the first repeating relay, a second repeating relay controlled by the second slow acting device, a stick circuit for the second repeating relay controlled 65 by a front contact of the first repeating relay in

multiple with a back contact of a third track relay, a highway crossing signal, and means starting operation of the signal when a train approaching the highway enters the second or the third or a fourth track section in accordance 70 with the condition of the first and second repeating relays.

2. In a signaling system for highway crossings on railroads, a plurality of track sections occupied successively by a train approaching the highway, a track circuit including a track relay for each section, a first slow acting device controlled by a back contact of a first track relay and a front contact of a second track relay in series, a first repeating relay controlled by the first slow 75 acting device, a stick circuit for the first repeating relay controlled by multiple back contacts of the first and second track relays, a second slow acting device controlled by a back contact of the first track relay, a front contact of the second track relay and a front contact of the first repeating relay, a second repeating relay controlled by the second slow acting device, a stick circuit for the second repeating relay controlled by a front contact of the first repeating relay in 80 multiple with a back contact of a third track relay, a highway crossing signal, and means starting operation of the signal when a train approaching the highway enters the second or the third or a fourth track section according as 85 the first and the second repeating relays are de-energized or the first repeating relay only is energized or the second repeating relay is energized.

3. In a signaling system for highway crossings 90 on railroads, a plurality of track sections occupied successively by a train approaching the highway, a first thermal relay set into operation when a train enters the first of the track sections, a first stick relay energized by a complete operation of the first thermal relay, a second thermal relay set into operation when the first stick relay is energized while a train occupies the first track section, a second stick relay energized by a complete 95 operation of the second thermal relay, a normally energized signal control relay at the highway, and means for de-energizing the signal control relay when a train enters the second or the third or the fourth track sections, respectively, according as the first and the second stick 100 relays are de-energized or the first stick relay only is energized or the second stick relay is energized.

4. In a signaling system for highway crossings 105 on railroads, a plurality of track sections occupied successively by a train approaching the highway, a first thermal relay set into operation when a train enters the first of the track sections, a first stick relay energized by a complete 110 operation of the first thermal relay, a second thermal relay set into operation when the first stick relay is energized while a train occupies the first track section, a second stick relay energized by a complete operation of the second thermal relay, a normally energized highway signal control relay, means for de-energizing the signal control relay when a train enters the second or the third or the fourth track sections according 115 as the first and the second stick relays are de-energized or the first stick relay only is energized or the second stick relay is energized, a signal governing train movements toward the highway, and means controlling the signal in accordance 120 with the condition of the first and the second thermal relays.

5. In combination, a portion of railway track intersected by a highway and divided into four sections traversed successively by a train approaching the highway, a track circuit including a track relay for each section, a highway signal for the intersection, two thermal relays arranged in cascade and serially energizable through a back contact of the first track relay and a front contact of the second track relay in series, two stick relays wholly separate from said thermal relays and distinctively conditioned in accordance with the complete operation of the thermal relays respectively for selectively starting operation of the highway signal upon entrance of a train into the second or the third or the fourth track sections.
6. In combination, a portion of railway track intersected by a highway and divided into four sections traversed successively by a train ap-

proaching the highway, a track circuit including a track relay for each section, a highway signal for the intersection, two thermal relays serially energizable through a back contact of the first track relay and a front contact of the second track relay in series, two stick relays wholly separate from the thermal relays and distinctively conditioned in accordance with the complete operation of neither, or one only, or of both of the thermal relays for selectively starting operation of the highway signal upon entrance of a train into the second or the third or the fourth track sections, respectively, a railway signal governing train movements approaching the highway, and control means for the railway signal including contacts of the two thermal relays in series, said contacts being closed only when the thermal relays are in their normal de-energized positions.

JOSEPH E. WILLING.
